UNITED STATES PATENT OFFICE.

CARL BACHMAN, OF NEWARK, NEW JERSEY.

DESIGN FOR A COMBINATION-TOOL.

54,365.

Specification for Design.

Patented Feb. 10, 1920.

Application filed August 5, 1919. Serial No. 315,548. Term of patent 3½ years.

To all whom it may concern:

Be it known that I, CARL BACHMAN, a citizen of the United States, residing at Newark, in the county of Essex and State of New Jersey, have invented a new, original, and ornamental Design for a Combination-Tool, of which the following is a specification, reference being had to the accompanying drawing, forming part thereof.

The figures of the said drawing clearly show my new, original and ornamental design; and in the drawings, Figure 1 is a side-view of one of the side-edges of the

combination tool; Fig. 2 is a top view of the same; Fig. 3 is a view of the opposite side-edge of the tool; and Fig. 4 is a bottom view of the same, and all said views clearly show my new, original and ornamental design.

I claim:—

The ornamental design for a combination tool as shown.

CARL BACHMAN.
